UNITED STATES PATENT OFFICE.

STANLEY C. HOPE, OF SPRINGFIELD, MASSACHUSETTS.

SAFETY RAZOR.

Application filed September 15, 1927. Serial No. 219,748.

My invention relates to safety razors, and particularly to means for storing extra blades in, and withdrawing them singly for use, from the handle, and also to means for clamping a blade in and removing it from the jaws.

My invention comprises with other features, a special magazine for holding a number of blades, means for placing and retaining the magazine in the handle, means for withdrawing the blades singly from the magazine and handle, means for securing a single blade in the clamping jaws, and means for releasing and withdrawing the blade from the jaws.

In order that my invention may be fully understood, I will first describe in detail the mode in which I at present, prefer to carry the invention into practice, and then particularly point out the novel features of the invention in the claims.

Reference is to be had to the accompanying drawings forming part of the application in which like parts are designated by the same letters in all the figures.

Figure 1 is a view of the top of a safety razor embodying my invention.

Figure 2 is a cross-sectional view of the upper part of the same on the line 2—2, Figure 1, showing the jaws opened.

Figure 3 is a transverse sectional view on the line 3—3, Figure 1.

Figure 4 is a cross-sectional view of the razor, showing the jaws closed, and the blades stored in the handle.

Figure 5 is a cross-sectional view of the handle showing one blade being withdrawn.

Figure 6 is a sectional view on the line 6—6, Figure 4.

In the drawings, number 7 designates the handle of the razor, which is hollow, and open at its lower end, and is provided with a removable cap 8 fitted over its lower end for closing it. A bayonet lock 9 is, by preference provided, for securing the cap 8 removably on the open end of the handle.

The upper end of the handle 7 is formed with a threaded stud 10, which is screwed detachably into a correspondingly threaded socket in the fixed lower blade-clamping jaw 11, which is formed with the usual serrated guard 12, and provided on its upper side with pins 13 to enter holes 14 in the blade and hold the same against lateral movement.

The lower jaw 11 is formed on its end with upwardly projecting ears 16, between which is pivoted the back of the upper movable jaw

17, which has recesses 18 in its opposite ends to fit and receive the ears 16. Pivot pins 19, fixed by preference in the opposite ends of the recessed back of the upper jaw turn in pivot holes in the ears 16, and permit the upper jaw to swing to and from the lower jaw.

The upper jaw is formed with pin holes 20, to correspond with and receive the pins 13 on the lower jaw when the jaws meet, and stiffen the jaws against relative lateral displacement.

The clamping jaws 11 and 17 are normally pressed together upon the blade 15 by a roughly U-shape plate spring 21, the lower plate of which is perforated to receive the handle stud 10 and is pressed upon the shoulder 22 of the handle by the lower jaw 11, when screwed upon the stud 10, as stated. The upper plate of the spring 21 fits and bears upon the upper surface of the upper jaw 17.

To separate the clamping jaws 11, 17, for removing and replacing the blade 15 therebetween, I prefer to cut in the back of the upper jaw 17, medially a forwardly extending slot 22^A, and on each side of said slot form on the underside of the upper jaw a downwardly projecting pair of ears 23, having upwardly extending recesses 24.

The recesses 24 serve as bearings for the pivot pin 25 of a cam lever 26 working in the slot 22^A, the cam bearing of which cam lever works on the upper surface of the lower jaw and the inserted stud 10, and has a rearwardly projecting arm 27, by which the cam lever can be raised as shown in Figure 2 to open the jaws or lowered as shown in Figure 4, to permit the spring 21 to close the jaws upon the blade.

To provide for storing a package of blades in the hollow handle 7, and for removing the blades therefrom singly as needed, I prefer to pack a number of blades 15 in a special case 28, of wood or other light and cheap material, having a medial axial squared bore 29 open at both ends, and opening forwardly through a narrower slot 30 in its front wall 31.

The packed blades are pressed against the inside of the front wall 31, by a longitudinal strip 32, acting as a follower, bearing against the rearmost blade and pressed thereagainst by springs 33 held in recesses 34 in the back of the bore 29, and pressing against both ends of the follower 32. All the blades in the case 28, except the foremost blade, are held against longitudinal displacement in the case by a cover 35 screwed over the open bottom of the case, and having a slot 36, in lon-

itudinal alignment with the foremost blade, to permit the same to be ejected therefrom.

The cap 8 is likewise provided with a blade-ejection slot 37, in longitudinal alignment with the slot 36 in the magazine or case cover 35. The follower 32 is tapered at both ends on its face as shown at 39, away from the front wall 31, to facilitate the introduction of the blades between the follower 10 and the front wall 31.

The case or magazine 28 containing the blades is fitted to and inserted in the front portion of the tubular handle 7. In the rear portion of said handle is fitted to slide longitudinally, a blade ejector carrier 40, to the face of which is attached a spring arm 41 having on its upper end a blade hook 42, which projects through and rides in the slot 30 in the wall of the case. The blade hook 42 projects forwardly enough to engage the upper edge of one blade only, and to the back of the carrier 40 is attached an ejector button 44, by a screw 43, projecting through and riding in a longitudinal slot 45, formed in the rear 25 of the handle wall.

The ejector carrier 40, is normally pressed upward by a coiled spring 46, inserted in a tubular guide 47 forming the lower portion of the carrier, the upper end of the spring 30 bearing against the solid upper head 48 of the carrier, and the lower end of the spring bearing against a plunger 49, fitted loosely in the tubular carrier guide 47, and having a stem 50 projecting through the constricted lower 35 opening 51 of the guide and resting on the inside of the handle cap 8, to hold the same against turning.

Thus, by simply depressing the button 44 with the finger, a single blade is easily ejected 40 so that it can be withdrawn by hand from the handle through the slots 36 and 37, for use in the clamping head of the razor as previously described.

It is evident that many changes may be made in the specific construction and arrangement of my invention herein described without departing from the boundaries thereof as defined by the following claims. 45

The means for storing and dispensing the blades shown and described herein are not 50 claimed herein but form the subject of a separate application for patent filed by me August 15th, 1928, Serial No. 299,755.

I claim as my invention:

1. A safety razor comprising a handle 55 having an end stud, a U-shape plate spring having its inner branch perforated to receive the stud, a fixed blade-clamping jaw screwing on the stud against the inner branch of the plate spring, a movable blade-clamping 60 jaw pivoted to the fixed jaw, the outer branch of the plate spring pressing on the outside of the outer jaw, and means for separating the movable jaw against the pressure of the plate spring from the fixed jaw. 65

2. A safety razor comprising a handle, a blade-clamping jaw fixed thereto, a movable blade-clamping jaw pivoted to the fixed jaw, a U-shape plate spring embracing both jaws and pressing them together, the movable jaw 70 being formed with a slot and pivot bearings on each side of the slot, a jaw-opening cam pivoted in said bearings, and bearing against the fixed jaw and having a handle projecting outwardly through said slot. 75

3. A safety razor in accord with claim 2 in which the U-shape plate spring has a slot registering with the slot in the movable jaw to receive the cam.

4. A safety razor in accord with claim 2 in 80 which the fixed jaw has upwardly projecting ears on its ends to and between which the back of the movable jaw which is narrowed is pivoted.

In testimony whereof I affix my signature.
STANLEY C. HOPE.
